(57) CLAIM

The ornamental design for a stove, as shown and described.

DESCRIPTION

FIG. 1 is a right-hand, front-lateral and top perspective view of the stove with its cover in the open position;

FIG. 2 is a front elevational view of the stove of FIG. 1;

FIG. 3 is an upper plan view of the stove of FIGS. 1-2; and,
FIG. 4 is right-hand lateral elevational view of the stove of the previous figures, illustrating the cover in the closed position, the left-hand lateral view of the stove being a mirror image of the right-hand lateral view thereof.
